ABSTRACT

Stay release interconnects securing point on the deck of a sailboat and a releasable stay for quickly and easily releasing the stay for disconnection and for reconnecting the releasable stay.

6 Claims, 4 Drawing Figures

SHEET 2 OF 2

FIG. 2

FIG. 3

STAY RELEASE

BACKGROUND

This invention is directed to a quick release mechanism including levers for the quick release and connection of releasable stays on sailboats.

The mast of sailboats must be supported with respect to the hull. This is conveniently accomplished by various types of stays. Sometimes, a stay is necessary to provide adequate mast support under some running conditions, but under other conditions, the release of that stay is necessary. This is true of backstays where the boom is too long to permit installation of a permanent backstay. Furthermore, running backstays are sometimes used to provide the additional support necessary in connection with the employment of larger sails during reaching and running.

Prior release mechanisms for running backstays and similar stays included block and tackle structures for tightening and loosening the running backstay. Another structure includes a lever pivotally mounted upon the deck with lever operation permitting tightening and loosening of the running backstay structure. Still another attachment and release mechanism for such stays includes the pelican hook, which permits attachment and release; however, such pelican hooks are normally of such structure that there is insufficient stroke to accomplish any substantial pulling in of the stay to tension it or permit its release for convenient disconnection. Such pelican hooks normally do not have a comfortable structure to engage by hand for ease of operation.

SUMMARY

In order to aid in the understanding of this invention, it can be stated in essentially summary form that it is directed to a stay release. The stay release comprises a toggle mechanism for manual operation with one end adapted to be connected to a releasable stay, and the other end adapted for connection to a deck fitting. The toggle mechanism has sufficient stroke and sufficient manually operable area for convenient operation.

It is thus an object of this invention to provide a stay release for releasable stay on a sailboat which is economic to manufacture, easy to use, and is of long-life. It is a further object to provide a stay release which includes a toggle mechanism so that, when pulled into tensioned position, longitudinal force on the stay release causes it to remain in the tensioned position. It is another object to provide a stay release which is suitable for use with a running backstay or a releasable inner forestay. It is still another object to provide a stay release which is fast and easy to operate. It is a further object to provide a stay release toggle mechanism which provides for substantially constant tension, with an increasing mechanical advantage with increasing tension on the stay during tightening of the stay. It is a further object to provide a stay release which is easy to install and which provides no substantial obstruction on the deck. It is yet another object to provide a stay release which has a sufficiently large operating stroke for convenient attachment and release of releasable stay.

Other objects and advantages of this invention will become apparent from a study of the following portion of the specification, the claims, and the attached drawings.

BRIEF DESCRIPTION OF THE DRAWINGS

FIG. 1 is a side-elevational view of a sailboat employing the stay release of this invention.

FIG. 2 is an enlarged side-elevational view of the stay release structure shown in the closed position.

FIG. 3 is a view similar to FIG. 2 showing the stay release in the open position.

FIG. 4 is a view of the release in the closed position, 10 seen generally along the line 4-4 of FIG. 2.

DESCRIPTION

In its preferred use, the stay release of this invention is employed on a sailboat. To illustrate the environment 15 and utility of the stay release, FIG. 1 illustrates sailboat 10 having mast 12. In order to support mast 12 with respect to the hull of the sailboat, forestay 14 and backstay 16 are employed in modern practice. Boom 18 is pivoted to the mast at its forward end to that a triangular sail can be mounted between the boom and the mast. The boom is sufficiently short to clear backstay 16. Thus, the triangular mainsail lies forward of backstay 16. Similarly, forestay 14 can carry a jib thereon. The jib conventionally runs on fittings which embrace 25 the forestay.

When reaching or running, the sailboat has additional stress on the mast caused by sail forces in the forward direction. In heavier wind conditions, it is desirable to connect a running backstay 20 from the mast to 30 the after portion of the boat hull, preferably on the windward side. Usually running backstay 20 has its mast end connected below the mast tip and has its lower end connected to the hull forward of the aft end of boom 18. Thus, running backstay 20 is in the way of 35 the boom when on the other tack. Thus, it must be disconnected when sailboat 10 is under other sailing conditions. Usually there are two running backstays, one on each side of the sail for connection to each side of the hull. Stay release 22 of this invention provides 40 quick connection and release of the stay.

Inner forestay 24 is provided so that sailboat 10 can be operated with two conventional jibs. One jib is run up forestay 14, and the other is run up inner forestay 24. However, in other sailing conditions, it may be desirable to run a single genoa-type jib on forestay 14. With a genoa jib, it would be difficult to bring the jib's 45 clew around inner forestay 24. Thus, inner forestay 24 is equipped with stay release 26, of the same structure as stay release 22. When stay release 26 is employed, when running a genoa jib on forestay 14, inner forestay 50 24 can be released and restrained close to the mast so that tacking the genoa jib is convenient.

The particular structure of stay releases 22 and 26 is 55 shown in detail in FIGS. 2, 3, and 4. Stay release 22 is shown in FIGS. 2 and 4 in the closed, stay-holding position. In FIG. 2, running backstay 20 is seen as being connected to turnbuckle 28 which is used for adjusting the length of the backstay. The lower end of turnbuckle 28 is engaged through connecting hole 30 in the upper 60 end of upper link 32. Lower link 34 has ring 36 secured to the lower end. Conventional snap shackle 38, see FIG. 2, is secured to ring 36 and is selectively engageable in deck fitting 40. Deck fitting 40 is in the form of 65 a loop through which the tongue of snap shackle 38 can extend. When the snap shackle is engaged, its tongue is held in place by the manually operable pin indicated in FIG. 2.

Toggle link 42 is pivoted to both upper link 32 and lower link 34. FIG. 3 illustrates the position of the pivot point between the links, and FIG. 4 illustrates additional detail of the links. Upper link 32 is a single flat, elongated rectangular bar. It carries a hand-hold 44 thereon. At its lower end, upper link 32 has pivot pin 46 by which it is pivoted to toggle link 42. Toggle link 42 actually comprises first and second spaced elongated rectangular bars 48 and 50. The rectangular bars are secured together at their upper end by hand-hold 52. Lower link 34 is formed of rectangular bars 53 and 54. The bars are joined at their lower end by ring 36. At their upper end, they are respectively pivoted to bars 48 and 50 by means of pivot pins 56 and 58, which lie on a common axis. As seen in FIG. 2, the longitudinal center line through stay release 22 is through ring 36 and connecting hole 30. When the stay release is in the shortened, closed position of FIG. 2, hand-holds 44 and 52 lie together and provide a limit stop. Pivot pin 46 is above the center line, as seen in FIG. 2, and the axis of pivot pins 56 and 58 is below the center line, as seen in FIG. 2. Thus, when in the closed position with the application of tension, the toggle is locked in the closed position. Furthermore, hand-holds 44 and 52 can be latched together to prevent accidental dislodgment.

When release is desired, when the major tension is removed from the stay, any whipping is removed from the hand-holds, and hand-hold 52 is pulled away. The size of the hand-holds permit large area grasp, both for disconnection and connection. Once the toggle link is pulled back past the toggle point, the stay release opens easily under stay tension. The open position is shown in FIG. 3. Once released, snap shackle 38 can be opened so that the running backstay can be secured in a convenient, out-of-the-way position. Stay release 26 is identical in structure and operation. Thus, both stays 20 and 24 can be quickly and easily released. Reconnection is also easily achieved by connected snap shackle 38 and making it fast with the stay release in the open position. Now, the stay release is closed from the FIG. 3 to the FIG. 2 position. The closing is enhanced by the use of large area hand-holds.

This invention having been described in its preferred embodiment, it is clear that it is susceptible to numerous modifications and embodiments within the ability of those skilled in the art and without the exercise of the inventive faculty. Accordingly, the scope of this invention is defined by the scope of the following claims.

What is claimed is:

1. A sailboat having a hull and a mast extending upward from said hull, a stay secured to said mast and extending toward said hull, a stay release interconnected between said stay and said hull for the quick release of the stay so that sails may be employed in the position occupied by the stay before its release, said stay release

comprising:

an upper link, a lower link, and a toggle link, said toggle link being pivotally mounted to both said upper link and said lower link;

connection means on said upper link connecting said upper link to said removable stay;

connection means on said lower link for removable connection to said hull of said sailboat, said connection means defining an axis through said stay release, said toggle link being pivotally connected to said upper link adjacent the lower end of both said upper link and said toggle link, said toggle link being pivoted to said lower link adjacent the upper end of said lower link and intermediate the ends of said toggle link, said pivot between said upper link and said toggle link, and said pivot between said lower link and said toggle link both being off said axis when said toggle link is in its raised position;

an upper hand-hold secured to the upper end of said upper link and a toggle hand-hold secured on the upper end of said toggle link, said hand-hold acting as stops to limit motion of said toggle link in the closed direction to a position wherein said toggle link lies substantially along said axis.

2. The stay release of claim 1 wherein said toggle link is formed of first and second bars, said toggle link handle being connected to both of said toggle link bars and maintaining spacing between said toggle link bars, said upper link lying between said toggle link bars when said toggle link is in its closed position, said pivot between said toggle link and said upper link comprising a pivot pin extending through both of said toggle link bars and said upper link.

3. The stay release of claim 2 wherein said lower link comprises first and second lower link bars, said lower link bars being respectively positioned outside of said first and second toggle link bars, a first lower bar pivot pin extending between said first lower bar and said first toggle link bar and a second lower link pivot pin extending between said second toggle bar and said second lower link bar, said first and second lower bar pivot pins lying substantially on the same axis.

4. The stay release of claim 3 wherein said means for connecting said lower link of said stay release comprises a connector secured to the lower end of both said first and second bars of said lower link.

5. The stay release of claim 4 wherein said connector is a U-shaped connector.

6. The stay release of claim 1 wherein said hand-holds lie adjacent each other when said stay release is in its closed position and said hand-holds extend respectively beyond said upper link and said toggle link so that said hand-holds can be temporarily tied together to secure said stay release in its closed position.
